UNITED STATES PATENT OFFICE.

WILLIAM R. CARROLL, OF MANY, LOUISIANA.

CAR-DOOR.

1,177,990.

Specification of Letters Patent.

Patented Apr. 4, 1916.

Application filed December 19, 1913. Serial No. 807,731.

To all whom it may concern:

Be it known that I, WILLIAM R. CARROLL, a citizen of the United States, residing at Many, in the parish of Sabine and State 5 of Louisiana, have invented new and useful Improvements in Car-Doors, of which the following is a specification.

This invention relates to improvements in sliding doors for railway cars, especially 10 freight cars and other similar structures, the invention consisting in the construction, combination, and arrangement of devices, hereinafter described and claimed.

One object of my invention is to provide 15 improved means for mounting a car door for sliding movement and to assist in the opening of the door.

Another object is to provide improved 20 means for locking the car door in open position.

In the accompanying drawings:—Figure 1 is a side elevation of a portion of a freight car provided with doors and operating, mounting and securing means therefor in 25 accordance with my invention. Fig. 2 is a vertical transverse sectional view on the plane indicated by the line *a—a* of Fig. 1. Fig. 3 is a similar view on the plane indicated by the line *b—b* of Fig. 1. Fig. 4 is a 30 detail horizontal sectional view of the sliding doors, showing the opposing edges thereof and showing the plates 11 and one of the supports 21 in plan. Fig. 5 is a detail side elevation showing one of the drums and its 35 spring, and with the cap omitted.

For the purposes of this specification a wall or side of a freight car is indicated at 1. On the outer side of the car wall, at a point below the bottom of the door opening 40 is a projecting flange 2 on the upper side of which, at the center thereof, are tracks 3 which are provided with rack teeth 4 the said tracks being narrower than said flange. A pair of sliding doors 5 are provided 45 which are movable toward and from each other. At the lower side of each door is a supporting wheel 6 which is peripherally grooved as at 7 to provide flanges 8 which are arranged on opposite sides of one of the 50 tracks 3 and bear directly on the supporting flange 2. These wheels have their upper sides arranged in substantially semi-circular recesses 9 and the axles 10 of said wheels are mounted in bearing openings in plates 11 which are arranged on opposite sides of the 55 doors and secured thereto by bolts 12.

Each door also has at its lower side a supporting gear 13 which is provided with spur teeth that engage the rack teeth of one of the tracks 4. These supporting gears 13 are also arranged in recesses in the lower sides of the doors and their axles 14 are mounted in bearing openings in plates 15 which are similar to the plates 11 and are secured on opposite sides of the doors by bolts 16. Each 60 gear 13 is provided on one side with a centrally arranged drum 17 on which is arranged a spring 18, one end of the spring being attached to the periphery of the drum and the other end thereof being secured on a screw 65 19 that connects the plates 15. A cap 20 is arranged on and serves to cover the spring. The springs are so coiled on the drums that they are wound up as the doors are opened, the spur teeth of the supporting gears 13 70 by engagement with the rack teeth of the tracks 4 causing said gears to be turned positively and prevented from slipping. Hence when the doors are in open position the springs, being wound, exert their tension 75 to turn the supporting gears in the required direction to close the doors, as will be understood. The doors are provided at their upper and lower ends with supports 21 which sustain them against pressure from 80 within the car. The upper sides of the doors are engaged by guides 22.

In order to enable the doors to be readily 85 opened I provide each door with an operating cord 23 which in practice is preferably a wire cord of suitable gage. Each cord is attached at one end to one of the doors as at 90 24, extends outwardly from the door and passes over a pulley 25 which is mounted on the car wall on a suitable supporting shaft 95 and at a suitable distance from one side of the door opening, the cord then hanging down from the pulley and being provided at its pendant end with a suitable handle 26 which may be readily grasped. It will be 100 understood that by drawing down on the pendant ends of the cord the doors will be opened and the springs of the supporting gears of the doors will be wound up.

Stops 27 are provided to limit the movement of the doors to open position, the said stops being here shown as springs which are attached to the wall 1. Each door is provided on its outer side with a pivotally mounted latch 28 which projects beyond its outer edge and is formed at its outer end with a cam face 29 and with a shoulder 30.

Each door also has a guide 31 for the latch 28. In association with each door and at a suitable distance from one side of the door opening is a catch 32 and a trip lever 33. The catches 32 are secured as by means of screws on the wall 1 and are adapted to be engaged by the shoulders 30 of the latches 28 when the doors are moved to open position so that said catches coact with said latches to automatically secure the doors in open position. The trip levers 33 are pivotally mounted on the car wall 1 as at 34 and are each provided with an arm 35. The said arms are in the paths of the latches 28, the said trip levers, normally, by gravity, assuming a vertical position. Hence as the doors open the latches 28 in passing over the arms 35 will before reaching the catches 32 turn the trip levers substantially to horizontal position. Hence in order to release the latches from the catches and permit the springs 18 to cause the coacting gears 13 and racks 4 to close the doors, it is only necessary to turn the trip levers 33 downwardly and thus cause their arms 35 to move upwardly under the latches 28 and disengage the latter from the catches 32.

A locking latch for securing the doors together in closed position is indicated in dotted lines at 36 in Fig. 1 and engages a keeper 43 which is also indicated in dotted lines in the same figure.

The supports 21 have flanges which bear on the outer sides of the door. These flanges

are beveled in opposite directions on their inner sides, as shown in Fig. 7, so that when the doors are closed the beveled inner surfaces of the flanges force the doors inwardly a slight distance. When the doors are drawn apart said beveled flanges permit them to move outwardly a slight distance. Hence the doors are prevented from being jammed and held tightly closed by pressure of the load in the car.

Having thus described my invention, I claim:

In a structure of the class described, a supporting track having a rack thereon, a door, a supporting gear for the door mounted in the lower end of the latter and engaging said rack, plates on opposite sides of the door having bearings for the shaft of said gear, a drum on one end of the shaft, a spring coiled on and secured at one end to a fixed point, a casing for the drum and spring and secured to one of said plates, the spring being arranged to be wound by the rotation of the gear when the door is moved in one direction so that the spring, when the door is released will coact with the gear and rack to move the door in the reverse direction.

In testimony whereof I affix my signature in presence of two witnesses.

WILLIAM R. CARROLL.

Witnesses:

J. M. ABINGTON,
Jno. L. McComic.
